(57) **CLAIM**

The ornamental design for a collapsible container, as shown and described.

DESCRIPTION

FIG. 1 is a side perspective view of a first embodiment of a collapsible container;

FIG. 2 is a perspective view of the first embodiment of the collapsible container;

FIG. 3 is a top plan view of the first embodiment of the collapsible container;

FIG. 4 is a bottom plan view of the first embodiment of the collapsible container;

FIG. 5 is a side perspective view of a second embodiment of the collapsible container;

FIG. 6 is a top plan view of the second embodiment of the collapsible container;

FIG. 7 is a bottom view of the second embodiment of the collapsible container;

FIG. 8 is a side perspective of a third embodiment of the collapsible container;

FIG. 9 is a top plan view of the third embodiment of the collapsible container;

FIG. 10 is a bottom plan view of the third embodiment of the collapsible container; and,

FIG. 11 is a front view of the above three embodiments of the collapsible container.
